UNITED STATES PATENT OFFICE.

LULU SNOW AGERTON, OF NASHVILLE, TENNESSEE.

DESIGN FOR A GARTER.

48,959.

Specification for Design.

Patented May 2, 1916.

Application filed November 19, 1915. Serial No. 62,433. Term of patent 14 years.

To all whom it may concern:

Be it known that I, LULU SNOW AGERTON, a citizen of the United States, residing at Nashville, in the county of Davidson and State of Tennessee, have invented a new, original, and ornamental Design for Garters, of which the following is a specification, reference being had to the drawing forming part thereof.

The figure is a front elevation of a garter showing my design.

Copies of this patent may be obtained for five cents each, by addressing the "Commissioner of Patents, Washington, D. C."

I claim:

The ornamental design for a garter, substantially as shown.

In testimony whereof, I have hereunto subscribed my name.

LULU SNOW AGERTON.
